Primary Examiner—Daniel Bui*(74) Attorney, Agent, or Firm*—Barley Snyder LLC(57) **CLAIM**The ornamental design for an electrical connector, as shown
and described.

DESCRIPTION

FIG. 1 is a front elevation view of an electrical connector,
showing my new design;

FIG. 2 is a top plan view thereof;

FIG. 3 is a rear elevation view thereof;

FIG. 4 is a right side elevation view thereof;

FIG. 5 is a cross-sectional view thereof, taken along the line
“5—5” in FIG. 1;

FIG. 6 is a top, front and left side perspective view thereof;

FIG. 7 is a top, rear and right side perspective view thereof;

FIG. 8 is a top, front and left perspective view thereof in
detached condition; and,FIG. 9 is a bottom, right, rear side perspective view thereof
in detached condition.**1 Claim, 9 Drawing Sheets**FIG. 1
